UNITED STATES PATENT OFFICE.

EDWIN J. AUGUSTIN, OF WAUWATOSA, WISCONSIN, ASSIGNOR OF ONE-THIRD TO GEORGE BAUER AND ONE-THIRD TO OTTO GRAY, BOTH OF MILWAUKEE, WISCONSIN.

PRESSURE-REGULATING VALVE.

1,392,617.

Specification of Letters Patent.

Patented Oct. 4, 1921.

Application filed March 6, 1920. Serial No. 363,752.

To all whom it may concern:

Be it known that I, EDWIN J. AUGUSTIN, a citizen of the United States, and resident of Wauwatosa, in the county of Milwaukee, 5 and State of Wisconsin, have invented certain new and useful Improvements in Pressure-Regulating Valves; and I do hereby declare that the following is a full, clear, and exact description thereof.

10 My invention pertains particularly to new and useful improvements in pressure regulating devices and has especial application to expansion valves for refrigerating apparatus.

15 In the use of a device of this nature in refrigerating apparatus for controlling the flow of the refrigerant from the high pressure side to the low pressure side of the apparatus, it is essential that the parts be so constructed as to eliminate a possibility of leakage. Most refrigerating apparatus expansion valves are automatically operated by means of a diaphragm, and as at present constructed such diaphragms are perforated, 20 and thus there is a possibility of the refrigerant leaking from one side to the other thereof. The primary object of this invention, therefore, is to provide an expansion valve in which the usual diaphragm is imperforate.

25 In devices of this character difficulty has also been experienced because of the cracking or breaking of the diaphragm due to excessive movement thereof. Consequently it is also the object of this invention to provide an arrangement whereby the parts of the device may be actuated by only slight movements of the diaphragm, and the bending of which is limited by suitable stops.

30 Another object of the invention is to provide means for preventing the freezing of a part of the mechanism on one side of the diaphragm.

35 Still another object of the invention relates to the means for forming an improved imperforate diaphragm for use in expansion valves for refrigerating apparatus.

40 With these objects in view the invention resides in the novel features of construction and combination and arrangement of parts 50 which will be hereinafter more particularly described and claimed.

In the accompanying drawing—

Figure 1 represents a vertical sectional view through an expansion valve constructed in accordance with the invention. 55

Fig. 2 is a transverse sectional view taken on the plane of the line 2—2 of Fig. 1.

Referring more particularly to this drawing, it will be seen that the main casing 1 of the device comprises an upper section 2 and a lower section 3, the adjacent edges of which are flanged as at 4 and secured together by bolts 5. In cross section each of the sections 2 and 3 is annular and the last mentioned section 3 is shouldered as at 6 to provide a diaphragm seat in which the peripheral edge portion of a diaphragm disk 7 is disposed. When the two sections of the casing 1 are secured together by the bolts 5, this diaphragm disk 7 is clamped therebetween as clearly shown in Fig. 1.

In its present construction the diaphragm disk consists of a relatively thick plate of properly treated rubber or similar material having substantially equivalent properties; together with a metallic disk 7'. The latter disk 7' is relatively thin and formed of flexible resilient sheet metal. Both of the disks and consequently the diaphragm are imperforate.

The upper end of the section 2 of the casing 1 is provided with a threaded bore 8 in which is disposed a longitudinal apertured plug 9. The inner end of the plug 9 is also counter-bored as at 10 to receive one end of an expansile coil spring 11 which surrounds the stem 12 of a pressure member, said member also including a disk-like head 13 mounted on the lower end of the stem 12 against which the opposite end of said spring 11 bears. The free end portion of the stem 12 extends into the threaded bore of the plug 9 which forms a guide therefor. The bore of the plug also receives a threaded screw 14.

From Fig. 1 it will be noticed that the inner wall of the section 2 is provided with an annular recess as at 15 to receive the head 13. A shoulder 16 is also formed as a result of this recess and the same is adapted to provide a stop to limit movement of the head 13 upward. As a result the diaphragm 7 is limited in its movements in

this direction. Inasmuch as the refrigerant used in the apparatus of which this invention is adapted to form a part is at a very low temperature, there is a tendency on the 5 part of the pressure member including the stem 12 and head 13 to freeze up to such an extent that responsive movement of the head with respect to the diaphragm is prevented. Therefore since the portion of the casing 1 10 above the diaphragm 7 is fluid tight, I dispose a quantity of oil or other liquid 15 therein sufficient to cover the head 13.

The lower portion of the casing 1 formed by the section 3 is the part through which 15 the refrigerant passes, and is consequently provided with an inlet 18 and an outlet 19. The flow of refrigerant through the inlet 18 is controlled by a valve 20 mounted on the lower end of a stem 21, the intermediate portion 20 of said stem being slidable through a guide formed in a spider 22. The portion of the stem 21 that projects above the spider is screw threaded and disposed in the socket of a stem 23 on which a diaphragm engaging 25 head 24 is mounted. An expansile spring 25 surrounds said stem 23 and respectively engages the spider 22 and head 24 so as to retain the latter in engagement with the diaphragm 7. It is to be noted that the 30 lower end of the stem 23 is normally spaced only slightly from the upper side of the spider 22, the latter being designed to form a stop to limit downward movement of the head 24 and diaphragm 7.

35 In practice the spring 11 is adjusted by means of the plug 9 for the pressure at which the device is to operate, and under normal conditions the refrigerant flows through the screened inlet 18 and the lower section 3 of 40 the casing to the outlet 19, it being understood that both inlet and outlet are connected with suitable piping to convey the refrigerant to desired parts of the apparatus. However, if the pressure of the refrigerant entering the inlet 18 exceeds the pressure with 45 which the spring 11 is holding the valve 20 open, it acts against the diaphragm 7 and moves the head 13 upwardly; the spring 25 causes the head 24 to follow the diaphragm 50 in its upward movement and consequently

closes the valve 20. The flow of refrigerant is thus cut off until the pressure thereto drops to normal. It will be seen that regardless of the pressure of the refrigerant, the diaphragm 7 can only move a limited extent 55 due to the engagement of the shoulder 16 by the head 13. Excessive movement of the diaphragm and resultant cracking thereof is prevented. When it is necessary to retain the valve 20 open for an extended period of 60 time, for instance for removing the refrigerant from the coils of the apparatus, the screw 14 is turned down until it forces the head 13 and diaphragm 7 downwardly to an extent to engage the stem 23 with the spider 65 22. This movement of the diaphragm is also relatively slight owing to the stop provided by the spider 22, but is sufficient to retain the valve 20 in open position.

60 By utilizing a screen for the inlet 18, the scale is trapped in the portion 18' and is thus prevented from entering the main portion of the casing to interfere with the seating of the valve 20.

75 I claim:

In a pressure regulating device, a casing, an imperforate diaphragm dividing the casing into two compartments, an inlet and an outlet to one of the compartments, a spider extending across said compartment between the inlet and the outlet and having a bore therethrough, a valve stem reciprocable into said bore and having a valve at one end adapted to seat on the outside of said inlet, a head mounted on the other end of the valve stem and adjustable longitudinally thereof, said head being adapted to engage the diaphragm, an expansile spring acting between the head and spider to urge the head into engagement with the diaphragm and simultaneously urge said valve onto its seat to close said inlet, and means on the other side of the diaphragm for urging the diaphragm and consequently the head and valve in the opposite direction.

90 In testimony that I claim the foregoing I have hereunto set my hand at Milwaukee, in the county of Milwaukee and State of Wisconsin.

EDWIN J. AUGUSTIN.
